HIGH-SPEED CAPPING MACHINE

Max Norman Schweizer, New York, N. Y., assignor
to Resina Automatic Machinery Company Inc.,
Brooklyn, N. Y., a corporation of New York

Application February 12, 1949, Serial No. 76,105

7 Claims. (Cl. 226—88)

1

This invention relates generally to capping machines, and more particularly to a type adapted to successively cap a large number of containers as they are moved on a conveyor belt.

An object of the present invention herein lies in the provision of a capping machine in which a relatively large number of caps may be applied to containers in rapid succession, the capping operation taking place while the containers are in transit.

Another object herein lies in the provision of a capping machine having a simple and efficient cycle of operation, the flow of caps and containers being simultaneous.

Another object herein lies in the provision of a capping machine, possessing the above advantages, in which there is an absence of sudden starts and stops of the container while in transit thereby eliminating practically all chances of spilling critical contents.

A further object of the invention lies in the provision of a high speed capping machine which is capable of convenient adjustment for accommodating various size containers and caps therefor.

A feature of the invention lies in the fact that when caps of a relatively small size are employed relatively higher capping speeds are available. With very small caps, speeds as high as two-hundred-fifty per minute are possible.

Another feature of the invention lies in the fact that there is a complete absence of star-wheels, and reciprocating levers common to many devices used heretofore.

Another feature of the invention lies in the fact that all timing linkages serving to coordinate individual caps with containers have been eliminated. In the present device, the neck of each container removes a cap from the cap supply means which lies in the path of the containers. In this way the feeding of caps from the cap supply means is automatically halted if there is no container in a cap receiving position.

Still another feature of the present invention lies in the provision of means which is adapted not only to tighten caps of the threaded type upon containers, but to seat and tighten into position caps of the bayonet or lug type as well.

These objects and features as well as other incidental objects and advantages will become more fully apparent during the course of the following disclosure, and be pointed out in the appended claims.

In the drawing to which reference will be made in the course of the following specifica-

2

tion, similar reference characters have been employed to designate corresponding parts throughout the several views.

Figure 1 is a longitudinal side elevational view of an embodiment of the invention.

Figure 2 is an end elevational view partly broken away to show details of internal structure.

Figure 3 is an enlarged fragmentary plan view of the cap gate shown with a cap in the container engaging position, as broken away from Figure 2.

Figure 4 is an enlarged fragmentary elevational view with added parts as seen from the plane 4—4 on Figure 3.

Figure 5 is an enlarged fragmentary sectional view as seen from the plane 5—5 on Figure 1, and showing a plurality of containers in operative positions. Certain of the parts have been removed for purposes of clarity.

Figure 6 is an enlarged fragmentary sectional view as seen from the plane 6—6 on Figure 5.

Figure 7 is an enlarged fragmentary elevational view of a portion of a container engaging belt, plane 7—7 on Fig. 6.

Figure 8 is an enlarged fragmentary sectional view as seen from the plane 8—8 on Figure 7.

Figure 9 is an enlarged fragmentary sectional view of a cap engaging rotor member.

Figure 10 is an enlarged fragmentary horizontal sectional view, as seen from the plane 10—10 on Figure 1.

Figure 11 is a fragmentary sectional view as seen from the plane 11—11 on Figure 5.

Figure 12 is a fragmentary horizontal sectional view as seen from the plane 12—12 on Figure 11.

The device, generally indicated by reference character 10, includes broadly a main frame element 11, conveyor belt means 12, container belt means 14, cap supply means 16, and cap positioning means 18.

The frame element 11 may be of any suitable form, such as that illustrated on Figures 1 and 2, and includes a plurality of brackets 20 for securing the device 10 to a floor (not shown), a bottom wall member 22, side walls 24, 25, 26, and 28, and a top wall member 30. Mounted upon the bottom wall member 22 is a prime mover 32, preferably in the form of a one-half horse-power electric motor, which through the belt 34 drives the gear reduction unit 36. A chain 38 connects the gear reduction unit 36 with shaft 40, thus transmitting power to the conveyor belt means 12.

The conveyor belt means 12 includes generally an endless linked belt 42, supported by the table 44, and the idler sprockets 46 and 48. As has

been mentioned the belt 42 is driven from the shaft 40 by means of a driver sprocket 50 engaging small protuberances 51 one on each link of the belt. The belt 42 normally travels in the direction indicated by the arrows 52 on Figure 1, and positive drive is assured by resilient guide members 54 and 56 which maintain the belt 42 in engagement with the sprocket 50. The conveyor belt 42 may be fed in any convenient manner, as for example by means of other conveyor belt means (not shown) which may be used not only to transport uncapped containers 100 to the device, but also to remove the containers after they have been capped. If desired the belt 42 may also be fed manually, although this is not practicable if the device is to operate at a relatively high speed.

The container belt means 14 moves in unison with conveyor belt means 12, by power transmitted through the chain 58, to shaft 60. Mounted upon the extremities of the shaft 60 are bevel gears 62 and 64 (see Figure 2) which mesh with bevel gears 66 and 68 on shafts 70 and 72 respectively. The last two mentioned shafts drive the sprockets, one of which is shown at 74 (see Figure 1) by which the chains 76 and 78 are driven. It might be mentioned at this point that the prime mover 32 serves to drive the means 12 and 14, and is capable of speed adjustment with respect to the other moving parts of the device to be subsequently described.

On Figures 7 and 8 there may be seen one segment of the chains which are substantially identical. Each link is provided with the usual connecting member 80 pivotally secured to the plates 82 by pins 84. The plates 82 are of a width considerably greater than the connecting members 80 and provide means for securing a resilient block 85 therebetween by suitable means such as the rivets 86. The outer surfaces 88 of the blocks 85 are adapted to engage the outer surfaces of the containers 100.

Turning now to Figure 5 there may be seen the adjustable guide rails 90 and 92 which are substantially similar in structure except that the guide rail 90 may be referred to as a left hand one and the guide rail 92 as a right hand one. Thus a description of guide rail 90 will serve to describe guide rail 92 as well, thereby avoiding needless repetition.

The guide rail 90 is generally elongated in shape, and rectangular in cross-section. The thickness thereof is preferably slightly less than the distance between the plates 82 of the links comprising the chain 76. As the plates 82 extend outwardly of the pins 84, when the chain 76 is in a stressed condition it is urged to follow the path of the edge 94 as illustrated on Figure 8. The rail 90 is also provided with a pair of longitudinally disposed slots 96 and 98, engaged by pintles 102 and 104. The last mentioned pins are secured to the extremities of pivotal arms 106 and 108 respectively, which are adapted to move the guide rail 90 toward and away from the belt 42 in order that containers 100 of various shapes and sizes may be conveniently accommodated. At the leftmost extremity of the guide rail 90 (as seen on Figure 5) there is provided a bracket 110 upon which is rotatably mounted the idler sprocket 112 about which the chain 76

passes.

Turning now to Figures 1 and 2, there may be seen the carriage members 114 and 116, upon which the table 44 and arms 106 and 108 are mounted. The arms are pivoted by manually

rotating the small handwheel 118. This in turn rotates shaft 120, whereby worm gears 122 and 124 may rotate the shafts 126 and 128. Through a somewhat similar linkage (not shown) the handwheel 130 displaces the guide rail 92. Since the guide rails 90 and 92 are each moved from two distinct points the edges 94 may be maintained parallel to the axis of the belt 42 at all times.

As the pintles 102 and 104 in their path of motion describe arcs rather than straight lines, it is necessary to provide means to maintain the chain 76 in a constant degree of tension. To accomplish this end, there are provided pivotally mounted rollers 132 depending from the guide rails 90 and 92, which engage cams 134 suitably fixed with respect to the auxiliary table 44. Thus as the guide rail 90 is moved outwardly or away from the belt 42 the roller 132 moves to contact the higher portion of the cam 134 which action forces the guide rail toward the idler sprocket 112, thereby eliminating the slack in the chain 76 which would otherwise occur. The initial tension may be regulated by means of adjusting screws 135 which changes the disposition of the cams 134 with respect to the table 44.

As the chains 76 and 78 are of a somewhat shorter effective length than the belt 42, separate guides are preferably mounted on the table 44 to maintain the containers 100 on the belt 42 when they are not engaged between the belts 76 and 78. Two of the guides are shown on Figure 1 at 136 and 138.

The cap supply means 16 includes generally a cap hopper 140, a cap chute 142, and a cap dispensing gate 144.

The cap hopper 140 may be of any suitable type such as that shown on Figures 1 and 2, which includes a rotating disk serving to propel caps 200 to the cap chute 142. Power to drive the hopper 140 is provided by a take off means which includes a clutch 146, a worm drive unit 148, a bevel gear pair 150, and a belt 152 which rotates the pulley 154.

The cap dispensing gate 144 is located at the lower terminus of the cap chute 142, and may be best seen on Figures 3 and 4. It includes a lower wall 156, preferably integral with that of the cap chute 142, a pair of resilient jaw members 158 and 160, and a positioning spring 162. The jaw members 158 and 160 are substantially similar, and are pivotally secured to the side walls 164 and 166 of the cap chute 142, at points 168 and 170. Since it is essential that the jaws be free to move with a minimum of friction, the mounting is relatively loose, the jaws being held in position by the small cotter pins 172. The jaws 168 and 170 each comprise a cap flange engaging portion 173, a main body portion 174 and a spring engagement portion 176. The coil spring 178 connects the spring engagement portions 176 and as may be seen on Figure 3 serves to urge the jaws toward a closed position. The spring 178 has a relatively low constant and is of a length such that it exerts but slight tension when in the position shown on Figure 3. That is to say, the spring is of a length slightly greater than the distance between the spring engagement portions when the mandible portions 173 are engaged by a cap 200. Accordingly, a slight pressure is all that is required to release the cap 200.

The cap positioning means 18 comprises broadly a cap leveling unit 180 (see Figure 4) and a rotor unit 182.

The leveling unit 180 includes a supporting frame 184 which is preferably integral with the upper superstructure 186 from which depend the forward leveling member 188, and the rear leveling member 190. The members 188 and 190 are generally similar, and each comprises an upwardly curved leading edge 192, and a planar portion 194. In order that there may be continuous action upon the caps 200 when the device 16 is in operation, the forward leveling member 188 is provided with a small recess 196, in which the leading edge 192' of the rear leveling member 190 may be disposed. The members 188 and 190 are each supported by four link members of equal length, two of which are shown at 198. The links are pivotally secured to the members 188 and 190 by means of mounting blocks 202, and to the supporting frame 184 in a similar manner. In the case of the upper mounting, however the links are partly disposed within narrow channels 204, whereby the movement of the links about the pivotal mounting is limited to a small arc. As shown on Figure 4 the forward leveling member 188 is shown at its uppermost limit of displacement, and the rear leveling member 190 is shown at its lowermost limit of displacement. Since the members 188 and 190 are mounted with respect to the supporting frame 184 in a manner resembling that of parallel rulers the lower surfaces 206 are maintained in a substantially horizontal plane, throughout the limited motion.

The rotor unit 182 (see Figures 1, 2, 9 and 10) provides means whereby the caps 200 may be rotated so as to finally seat them upon the necks 326 of the containers 100. As will become more fully apparent, it is readily adapted by a convenient adjustment for use not only with screw type caps which are secured by a simple twisting motion, but also with the lug or bayonet type cap, which requires a leveling motion to prevent the jamming of the interengaging parts, and a slight twisting motion for final engagement.

As may be seen on Figure 2 the rotor unit 182 is driven by a second prime mover 208, through a chain 210, which engages a sprocket 212, on shaft 214. Disposed within an outer casing element 216 (Figures 2 and 10) is a portion of the shaft 214 upon which are mounted three worm gear 218, 220, and 222, which drive the horizontally disposed gears 224, 226, and 228, on shafts 230, 232, and 234 respectively. Driving sprockets 236, 238 and 240 are also mounted upon shafts 230, 232, and 234, respectively; and through sprocket chains 242, 244, and 246, transmit motion to sprockets 248, 250, and 252 on shafts 254, 256, and 258. The driven sprockets 248, 250, and 252 are provided with two teeth more than the driving sprockets 236, 238, and 240, which causes the shafts 254, 256, and 258 to rotate at a slightly slower speed than the shafts 230, 232, and 234. The last six mentioned shafts are connected through universal type couplings 260 to the rotors 262, and rotor 262' which are substantially similar in construction with the exception of the rotor 262' driven by shaft 254. As may be seen on Figures 1, 2, and 9, the rotors are each supported by the frame 184 by a pin 263 contacting the sides of a channel 264, and a threaded adjusting screw 266. This structure permits the individual rotors 262 to be moved toward or away from the rotor directly opposite, thereby providing for the accommodation of different sizes of caps 200.

On Figure 10 may be seen an enlarged sectional

view of the rotor 262'. The rotors 262 are generally similar to rotor 262' but lack certain parts to be noted hereinafter. A description of rotor 262', therefore, will serve to describe the rotors 262, thereby avoiding needless repetition.

The rotor 262' includes a casing element 268, a reversing means 270 (not present in rotors 262) and a cap engaging member 272. The casing element 268 is of irregular configuration and includes the aforementioned channel 264 and a threaded orifice 265 in which the adjusting screw 266 is engageable.

Power is transmitted through the coupling 260 to the shaft 274. The bevel gear 276 is concentric with shaft 274 but is not rigidly secured thereto. In the position shown on Figure 9, however, the sliding clutch means 278 has been moved upwardly so that the claw member 280 which is slidably keyed to the shaft 274 engages the claw member 282 which is integral with gear 276. Power is thus transmitted through the idler gear 284 to the driven gear 286 which is secured to the shaft 288 by the pin 290. In this position therefore the direction of the power transmitted to the shaft 274 is reversed when transmitted to shaft 288. By moving the lever 294 upwardly the member 280 is disengaged from the member 282, and the claw member 292 then engages the claw member 294 integral with the gear 286. In this later position the power is transmitted directly from the shaft 274 to the shaft 288 without reversal of direction.

The cap engaging member 272 is preferably in the form of a first flange member 296, and a second removable flange member 298, between which is maintained a resilient annular member 300 preferably formed from rubber or similar material. A screw 302 permits the removal of the flange member 298 should it be necessary to replace the annular member 300.

As has been mentioned, the rotors 262 are similar to the rotor 262' except that the reversing means 270, including the clutch mechanism 278 and the gears 276, 284, and 286, is eliminated.

The rotor cap supply means 16, together with the cap positioning means 18, are not only capable of adjustment with respect to different sized caps 200, but are also adjustable in order to accommodate containers 100 having different heights. The means to accomplish this end are perhaps best seen on Figures 1 and 2. As may be seen thereon the superstructure 186 is supported upon four shafts 302, which are slidably disposed with respect to the guides 304 mounted on the upper top wall member 30; that is to say the superstructure may be moved along an axis parallel to the shafts 302, whereby the position of the annular members 200 is altered to conform to the particular containers being capped. Precise adjustments are obtained by manually rotating the handwheel 306, on shaft 308. Motion is transmitted through the gear pair 310 and worms 312 to the threaded shafts 314 mounted in thrust bearings 316, which in turn raise or lower the threaded brackets 318 upon which the superstructure 186 rests. There are two brackets 318 and associated structure, only one of which is shown in the drawings.

Operation

The device is readied for operation by loading the hopper 149 with a sufficient number of caps 200, and adjusting the container belt means 14 and cap positioning means 18 to conform to the particular size container 100. For example,

in the case of a container of relatively large configuration, the superstructure 186 may be raised by the hand wheel 306; the rotors 262 and 262' are adjusted outwardly by the screws 266; and the guide rails 98 and 92 are also moved outwardly by the handwheels 112 and 130. The prime movers 32 and 298 may then be started by depressing the switches 320 and 322. In a short time the cap chute 142 has been filled with caps 280, and the device is now ready for the introduction of uncapped containers 100 which are placed upon the belt 42 at the left of the device as seen on Figure 1. As the container 100 moves toward the right it is engaged between the belt means 14. At this point the container 100 is securely engaged by the device and is moved toward the cap gate 144 (see Figures 4 and 5). As the container moves past the gate 142 the neck 324 engages the flanged portion 326 of the cap 280, and forces it against the engaging portions 178 whereby they are moved outwardly against the action of the spring 178. The cap is prevented from slipping off the neck of the container at this point by the positioning spring 132. Should the cap 280 not be axially aligned with respect to the axis of the container it is made so by contact with the surface 288 of the forward leveling member 182. Subsequent travel to the right brings the cap into contact with the resilient members 300 of the rotor members 262 and 262', which are rotating in the direction of the arrows shown on Figure 10. As viewed from above, therefore, the caps are twisted clockwise. The twisting motion is continued as the container progresses to the right, and is successively maintained as the cap contacts the annular members 300 of the second and third pair of rotor members 262. When the container 100 emerges from the device 10, the cap has been fully seated upon the neck 324, and is ready for subsequent handling.

In the above sequence of operation the lever 294 of the rotor member 262' has been moved to its uppermost position in order that the rotor member 262' rotate in the same direction as the other rotor member 262. This is the proper adjustment when using screw type caps such as those shown on Figure 4. When the lug or bayonet type of cap is employed, the lever 294 is moved to its lowermost position thereby reversing the direction of rotation of the annular member 300 of the rotor 262'. Since the rotor 262' rotates at a slightly slower speed than the rotor 262 directly opposite, there will be a resultant torque tending to rotate the cap counterclockwise as seen from above. Should the cap at this point have failed to seat owing to the lugs on the neck of the container being disposed immediately beneath the lugs of the cap, the counterclockwise torque will serve to rotate the cap whereby the lugs may be disengaged permitting the cap to drop to the proper level for seating. The second and third sets of rotors 262 then provide the clockwise torque necessary to finally engage the cap so that the lugs upon the cap will be disposed beneath the lugs of the containers.

By virtue of the fact that the speed of travel of the containers 100 is governed by the speed of the prime mover 32, while the speed of the rotors 262 (and 262') is governed by the speed of the prime mover 298, these speeds may be independently adjusted to produce the desired mode of operation. Since the cap supply means 16 is coupled to the drive for the said rotors, the faster the capping operation is performed the

greater will be the supply of caps, in the position to be picked up by the necks of the containers.

While I have shown three pairs of rotors which act upon the caps, the number of pairs may be increased or decreased depending upon the speed of operation desired. I have determined by actual test that three pairs are most desirable, particularly when one of the rotors in one of the pairs is used to seat bayonet or lug type caps, by a reversal of its normal rotation.

As described in connection with the description of the structure shown on Figure 10 of the accompanying drawings, the speed of rotation of the shafts 254, 256, and 258 is slightly less than the speed of rotation of the shafts 230, 232, and 234. In this manner the movement of the container as it passes the annular member 300 is compensated for. This results in improved operation, especially at high capping speeds. At lower capping speeds, the sprockets 248, 250, and 252 may have the same number of teeth as the sprockets 236, 238 and 240.

Where it is desired that the device be used only with straight screw caps (as contrasted with caps having bayonet lugs), the rotor 262' may have the reversing mechanism absent.

When containers are encountered which have necks that are eccentric with respect to their bodies, neck guides (a spaced and parallel pair) may be used. Such guides are indicated by reference character 330 on Figures 1 and 4. Such guides are independently adjustable by means not shown, and the bottles or containers when so positioned by the neck guides may shift slightly in a lateral direction with respect to their path of travel by virtue of the resilient blocks 85.

It may thus be seen that I have invented a novel and useful improvement in high speed capping machines in which there has been achieved a highly simplified cycle of operation. The invention permits of extremely high capping speeds to a degree previously unobtainable, and yet allows the containers to be gently handled whereby spilling of the contents of the uncapped containers is practically eliminated. The device may be constructed with considerably fewer moving parts than has been heretofore possible, and accessibility for repairs may be less frequent and of a less serious nature. The device may be operated by those possessing only ordinary skill, and with but ordinary care there is no danger to the person of the operator.

I wish it to be understood that I do not consider the invention limited to the exact details of structure set forth and described in the above specification, for obvious modifications will occur to those skilled in the art to which the present invention relates.

I claim:

1. A capping machine for use in applying caps to uncapped containers including: a conveyor belt means, and a cap positioning means; said cap positioning means including a plurality of rotor members engageable with said caps and serving to engage said caps upon said containers; said rotor members being disposed upon opposite sides of said caps and containers as they are transported past said rotor unit by said conveyor belt means; all of said rotor members being capable of rotation in a first direction, and one only of said rotor members being capable of rotation in a second direction opposed to said first mentioned direction.
2. A capping machine for use in applying caps

to uncapped containers including: a conveyor belt means and a cap positioning means; said cap positioning means including a plurality of rotor members engageable with said caps and serving to engage said caps upon said containers; said rotor members being disposed upon opposite sides of said caps and containers as they are transported past said rotor member by said conveyor belt means; means for driving all of said rotor members in a first direction, and a portion only of said plurality of rotor members having selective rotation reversal means for selectively and simultaneously driving said portion in a second direction opposed to said first direction, as the remainder of said rotor members are driven in said first direction.

3. A capping machine for use in applying caps to uncapped containers including: a conveyor belt means and a cap positioning means; said cap positioning means including a plurality of rotor members engageable with said caps and serving to engage said caps upon said containers; said rotor members being disposed on opposite sides of said caps and containers as they are transported past said rotor members by said conveyor belt means; means for driving all of said rotor members in a first direction of rotation, and selective rotation reversal means for selectively and simultaneously driving a portion only of said plurality of rotor members in a second direction opposite said first direction.

4. In a capping machine for applying caps to uncapped containers, a rotor unit; said rotor unit including a plurality of adjustable rotors engageable with said caps; means for driving said rotors in a first direction; second means for selectively and simultaneously driving a portion only of said plurality of rotors in said first direction or a second opposed direction.

5. In a capping machine for applying caps to uncapped containers, a rotor unit; said rotor unit

including a plurality of adjustable rotors engageable with said caps; means for driving said rotors in a first direction; second means for selectively and simultaneously driving one only of said rotors in said first direction or a second opposed direction.

6. In a capping machine for use in applying caps to containers, a rotor unit comprising: a plurality of rotors engageable with said caps and means for driving said rotors in a first direction; a single rotor only of said plurality of said rotors having selective rotation reversal means driven by said first mentioned driving means simultaneously in said first direction or a second direction opposite to said first direction.

7. In a capping machine for use in applying caps to containers, a rotor unit comprising: a plurality of rotors engageable with said caps and means for driving said rotors in a first direction at a first given speed; a portion only of said plurality of said rotors driven by said first mentioned driving means having selective rotation reversal means for simultaneously rotating said single rotor in said first direction or a second direction opposite said first direction at a second speed greater than said first mentioned speed.

M. NORMAN SCHWEIZER.
